UNITED STATES PATENT OFFICE.

WARD B. STORY, OF NEW YORK, N. Y., ASSIGNOR TO WARD B. STORY COMPANY, INC.,
OF NEW YORK, N. Y., A CORPORATION OF NEW YORK.

REGISTER DEVICE FOR FEEDERS.

1,161,014.

Specification of Letters Patent. Patented Nov. 16, 1915.

Application filed March 12, 1912. Serial No. 683,331.

To all whom it may concern:

Be it known that I, WARD B. STORY, a citizen of the United States, residing in the borough of Brooklyn, county of Kings, city 5 and State of New York, have invented a certain new and useful Register Device for Feeders, of which the following is a specification.

This invention relates to machines for feeding sheets to a printing couple, to a folder, or for feeding insert sheets or covers to the folder of a web printing machine.

The objects of the present invention are the same as there set forth in the specification of my application for patent, filed March 12, 1912 and numbered serially 15 683,330, but are accomplished by means of a different arrangement of mechanism.

In the drawings, Figure 1 is a plan view, 20 with parts broken away, of the operative portions of a device embodying the invention. Fig. 2 is a section on the line 2—2 of Fig. 1. Fig. 3 is a side elevation of the retarding and accelerating cam. Fig. 4 is 25 an edge view of the same. Fig. 5 is a view similar to Fig. 3, with the cam parts in a different position from that shown in Fig. 3. Fig. 6 is a similar view of the retarding cam part. Fig. 7 is a similar view of the 30 accelerating cam part. Fig. 8 is a diagrammatic view of a modification. Fig. 9 is a detail view of a portion of the device shown in Fig. 8. Fig. 10 is a plan view of a portion of the device illustrated in Fig. 8. Fig. 35 11 is a diagrammatic view of a modification.

In all of the views, like parts are designated by the same reference characters.

Referring particularly to Figs. 1 to 8 inclusive, the feed rollers 1, 1 are rotated by 40 suitable mechanism, at normal speed. These rollers are adapted to have the sheets fed to them from any form of feeding device, such as a pile feeder or continuous feeder. The feeding devices similar to that shown in 45 my co-pending application, before identified, may be employed in feeding the sheets to the feed rollers 1, 1. From the feed rollers, the sheets pass upon the tapes 2 between the upper gage roller 3 and lower gage roller 4. From these gage rollers, they 50 pass between the feed table rollers 5, 5, which are rotated at normal speed and then pass from the table 6, so as to be fed between the rolls of the printing couple. Referring more particularly to Figs. 1 and 2,

the table 6 has edge guides 7, 7 for controlling and defining the edge of the sheet. These guides are carried by suitable supports 8 from the frame 9, of the machine. The continuously operated driving shaft 10 drives the shaft for the feed rollers 1, 1, and feed table rollers 5, 5 by means of bevel gears. The lower gage roller 4 turns with the shaft 11. This roller is divided into as many sections as are necessary. A lay shaft 12 is arranged parallel with the shaft 11. For the purpose of rotating the gage rollers, I provide mechanism which comprises a spur gear 13, which is loosely mounted upon the shaft 11. This spur gear meshes with and is 60 driven by a spur gear 14, which is fixed on the lay shaft 12. This lay shaft is driven by suitable gearing 14', from one of the shafts which support the feed table rollers 5, 5, which in turn is driven by the bevel gear from the shaft 10, as shown. The connections between the shaft 11 and spur gear 13 are as follows: A toothed sector 15 is fixed upon the shaft 11, and turns with the latter. A second toothed sector 16 is in engagement with the toothed sector 15, and is carried upon a short shaft 17. This short shaft is supported in bearings in the spur gear 13, and rotates with the latter. The shaft carries a crank 18 on the other side 65 of the spur gear from the toothed sector. On the end of the crank is a pin 19, which may be bushed with a roller, as shown, for reducing friction. This pin engages with a cam 20, which surrounds the shaft 11. The 70 cam is supported concentrically in relation to the shaft by being carried upon a bushing 21, attached to the frame 9. The cam 20 is formed of two parts—an accelerating cam part 22, and a retarding cam part 23; each 75 being shown in Figs. 6 and 7, respectively. The retarding cam part 23 is attached fixedly to the frame 9. The accelerating cam part is capable of rotary motion in respect to the bushing. Its position is determined 80 by means of mechanism which includes worm teeth 24 on the cam part, and a worm 85 25 carried by the frame and engaging with the worm teeth. A hand wheel 26 gives motion to the worm, and allows a limited but 90 sufficient rotary movement of the accelerating cam part. The lower gage roller has a high part 27, extending a sufficient distance 95 to propel the sheet to two rollers 5, 5, and a low part 28 extending through the re- 100 105 110

mainder of the periphery. The gage 29 is secured to the low part, somewhat in advance of the beginning of the high part, as shown in Fig. 2.

5 The device as described, operates as follows: Referring to Figs. 1, 2 and 3, the sheets are singly fed to the feed rollers 1, 1 and are passed from them to the gage, by means of the tapes 2. The lower gage roller 10 is rotated at normal speed, and is of such size that it makes one complete revolution for each sheet. The shaft 11 will be rotated through the agency of the spur gears 13, the lay shaft 17 and the toothed sectors. If 15 the cam 20 were in the form of a circular groove concentrically located in relation to the shaft 11, the shaft 17 would not be oscillated in its bearings by engagement with the crank pin with the cam. As, however, 20 the cam slot is distorted, as shown, the pin following this cam slot will oscillate the shaft 17 to an extent which depends upon the shape of the slot and the position that the pin occupies in the cam. When the pin 25 engages with the low part of the cam, the shaft is oscillated in one direction, and with it the two toothed sectors are relatively moved, which has the effect of turning the shaft 11 slightly in advance of the spur gear 13. When the pin is in the high part 30 of the cam, it has the reverse effect and slightly retards it. The shape of the cam is such that when the gage 29 is rising through the opening of the table, and is about to 35 engage with the sheet which is being fed forward by the tapes, it will begin to be retarded. As the sheet is being fed forward at normal speed by means of the tapes, the retardation of the movement of the gage 40 will bring it into engagement with the forward edge of the sheet. This retarded movement will continue until the stop has passed under the upper gage roller 3, and until the forward edge of the high part 27 of the 45 lower gage roller engages with the sheet and pinches it against the upper gage roller 3. The sheet will then be fed forward by engagement with these two rollers. While the sheet is in engagement with the gage and 50 the latter is being retarded, the pin 19 will be in engagement with the retarding part 23, of the cam. When the high part of the roller is in engagement with the sheet, the pin will have entered the accelerating part 55 22 of the cam. The effect of this will be to oscillate the shaft 17, turn the sectors and advance the gage roller relatively to the shaft 11. The effect of this will be to accelerate the sheet so that its speed will then 60 be equal to normal. This acceleration will continue until the sheet is fed sufficiently far so that it will be gripped between the feed table rollers 5, 5. The operator, by adjusting the position of the hand wheel 26, can 65 displace the accelerating cam part 22 in re-

lation to the retarding cam part 23, as shown in Fig. 5. The effect of this will be to continue the acceleration for a longer period than when the cam parts are arranged, as in Fig. 3, thus continuing the movement at 70 a speed above normal. By moving the accelerating cam part in the other direction from that shown in Fig. 5, the acceleration will be decreased and the total movement of the sheet will be below normal. 75

From the foregoing description, it will be apparent that I attain the same objects by the double cam that I do by the two-cam arrangement described in my co-pending application before referred to. 80

Fig. 8 illustrates a modification of the invention in which the gage 29, instead of being supported upon the gage roller, is supported upon the tapes 2. In this view is shown a spur gear 30, on the shaft 11, 85 for rotating the gage roller, and this spur gear engages with an intermediate spur gear 31, which in turn, is rotated by the spur gear 13. Fig. 8 shows a convenient way of grouping the parts, the spur gear 31 being 90 mounted upon the same shaft which supports the cam 20. This impression cylinder 33, transfer cylinder 34 and delivery cylinder 35 are arranged in the usual manner. According to the apparatus illustrated in 95 Fig. 8, the roller 4 is of such diameter that the type will make one complete revolution for each sheet that is fed. The gage, when supported by flexible carriers, will have its movement retarded in precisely the same manner as the gage 29 which is attached directly to the lower gage roller. In order to avoid any chance of slipping of the tapes upon the roller, the latter may be provided with notches 36, which will be engaged by 100 teeth 37 carried by the tapes. 105

According to the modification of the invention illustrated in Fig. 11, I employ accelerating rollers 38, which are geared to rotate at a speed above normal. According to 110 this embodiment of the invention, the cam 20 is so made that it accelerates only and does not retard the movement of the gage rollers while controlling the sheet. The gage, therefore, when engaged by the sheet, 115 moves at normal speed. The sheets are brought into engagement with the gage by acceleration of the rollers 38, 38, which has the same effect as the retardation of the gage in the devices previously described. 120

The acceleration rollers 38, 38 may be employed in the structure illustrated in Fig. 8, in which event the sheet will be accelerated and the gage will be retarded. 125

In accordance with the provisions of the patent statutes, I have described the principle of my invention, together with the apparatus which I now consider to represent the best embodiment thereof; but I desire to have it understood that the apparatus shown 130

is merely illustrative and that the invention can be carried out in other ways.

Having now described my invention, what I claim as new and desire to secure by Letters Patent, is:—

1. A registering device having a movable gage, means for feeding a sheet to the gage, means for feeding the sheet from the gage, and means for varying the movement of the gage and for accelerating or retarding the movement of the last named feeding means.

2. A registering device having means for feeding a sheet to a gage, a movable gage; means for feeding the sheet from the gage; and common means for varying the movement of the gage and for accelerating or retarding the movement of the last named feeding means.

3. A registering device having means for feeding a sheet to a gage; means for feeding the sheet from the gage; and common means for varying the movement of the gage and for accelerating or retarding the last named feeding means, said common means being adjustable while the feeding means are in operation.

4. A registering device having means for feeding a sheet to a gage, a movable gage, means for feeding the sheet from the gage, a single cam, and connections between the cam and the gage, and between the cam and the last named means for varying the speed of movement of the gage and for accelerating or retarding the said last named means.

5. A registering device having sheet feeding means, a movable gage, a roller, a single cam, and connections between the cam and the gage, and between the cam and the roller for varying the speed of movement of the gage and for accelerating or retarding the roller, and means for adjusting the position of the cam for varying the amount of acceleration of the roller.

6. A registering device having a frame, a feeding means, a movable gage, a roller and a two-part cam, one part being rigidly connected to the frame, and the other part co-operatively connected to the first part, connections between the cam and gage, and means for varying the angular relation of the two parts of the cam.

7. A registering device having means for feeding a sheet to a gage, a movable gage, means for feeding the sheet from the gage, a cam, and means co-operating with the last named feeding means and the cam for varying the movement of the gage and for accelerating or retarding the movement of the said feeding means.

8. A registering device having means for feeding a sheet to a gage, a movable gage, means for feeding the sheet from the gage, an adjustable cam, and means co-operating with the last named feeding means and the cam for varying the movement of the gage

and for accelerating or retarding the movement of the said feeding means.

9. A registering device having means for feeding a sheet to a gage, a movable gage, means for feeding the sheet from the gage, an adjustable cam, means for varying the adjustment of the said cam while the machine is in operation, and means co-operating with the last named feeding means and the cam for varying the movement of the gage and for accelerating or retarding the movement of the said feeding means.

10. A registering device having means for feeding a sheet to a gage, a moving gage, a gage roller, means for driving the gage and gage roller in unison, a cam, and connections between the cam and gage roller for varying the speed of the roller relatively to that of the driving means.

11. A registering device having means for feeding a sheet to a gage, a movable gage, a gage roller and means for rotating the same, an adjustable cam, connections between the cam and gage roller for varying the speed of the roller relatively to that of the driving means, and means for adjusting the cam while the machine is in operation.

12. A registering device having means for feeding a sheet to a gage, a shaft carrying a gage and means for taking the sheet from the gage, means for driving the shaft, a cam, and means carried by the driving means and co-acting with the cam, for varying the speed of the taking means and gage relatively to that of the driving means.

13. A registering device having means for feeding a sheet to a gage, a shaft carrying a gage and means for taking a sheet from the gage, means for driving the shaft, a cam, an arbor carried by the driving means, a crank, on the arbor, engaging the cam, connections between the shaft and the arbor for rotating the shaft relatively to the driving means.

14. A registering device having means for feeding a sheet to a gage, a gage roller and means for rotating the same, a gage carried by the gage roller, a cam, and connections between the cam and gage roller for varying the speed of the roller relatively to that of the feeding means.

15. A registering device having means for feeding a sheet to a gage, a gage roller, and means for rotating the gage roller at the speed of the feeding means, a gage carried by the gage roller, a cam, and connections between the cam and gage roller for varying the speed of the roller relatively to that of the driving means.

16. A registering device having sheet feeding means, means for retarding and accelerating the movement of the sheet, and means for varying the amount of acceleration, said latter means being adjustable while the feeding means are in operation.

17. A registering device having sheet

feeding means, means for retarding the sheet, means for accelerating the speed of the sheet, and means for varying the amount of acceleration.

5 18. A registering device having sheet feeding means, a gage for retarding the movement of the sheet, means for accelerating the movement of the sheet, and means for varying the amount of acceleration.

10 19. A registering device having sheet feeding means, a moving gage, means for retarding the movement of the gage to lower the speed of travel of the sheet, means for accelerating the speed of the sheet after retardation, and means for varying the amount of acceleration.

15 20. A registering device having sheet

feeding rollers, a moving gage for retarding the speed of movement of the sheet, means whereby the sheet is gripped by the rollers 20 after gaging, and means for accelerating the speed of the rollers.

21. A registering device having sheet feeding rollers, a moving gage for retarding the speed of movement of the sheet, means 25 whereby the sheet is gripped by the rollers after gaging, and means for accelerating or retarding the speed of the rollers.

This specification signed and witnessed this 7th day of March, 1912.
